(57) **CLAIM**

The ornamental design for an anchor device, as shown and described.

DESCRIPTION

FIG. 1 is a back view of the anchor device;

FIG. 2 is a bottom view thereof;

FIG. 3 is a front view thereof;

FIG. 4 is a left side view thereof;

FIG. 5 is a perspective view thereof;

FIG. 6 is a right side view thereof; and,

FIG. 7 is a top view thereof.

The broken line showing of an anchor device is for the purpose of illustrating portions of the article and forms no part of the claimed design.
